UNITED STATES PATENT OFFICE.

WILLIAM AUG. GIBSON, OF OLD JEWRY, LONDON, ENGLAND.

HYDRAULIC ELEVATOR.

SPECIFICATION forming part of Letters Patent No. 367,098, dated July 26, 1887.

Application filed January 7, 1886. Serial No. 187,916. (No model.)

To all whom it may concern:

Be it known that I, WILLIAM AUGUSTUS GIBSON, a citizen of the United States, residing at Old Jewry, in the city of London, England, have invented a new and useful Improvement in and connected with Hydraulic Elevators, of which the following is a specification.

This invention relates to hydraulic lifts or elevators such as are now in ordinary use and in which the travel of the cage is governed by the motion of a piston inclosed in a cylinder and acted upon by hydraulic pressure; and it consists in the combinations and arrangements of parts, as hereinafter described.

To clearly explain my invention, and to show how others versed in the art may practically carry it into effect, reference is made to the accompanying drawings and letters marked thereon to designate the various parts of the apparatus, and in which—

Figure 1 represents an elevation of the lift-cylinder and the improved constructions in connection therewith; Fig. 2, a detail section of the ordinary eduction-valve, and Fig. 3 a detail section through the valve controlling the supply from the source of power.

A is what may be called the "lift-cylinder," as in it travels the piston B, the rods b of which carry the pulleys around which the cage-ropes 30 pass.

C represents the ordinary circulating-pipe used in what are known as the "Standard," "Otis," or "Hale" elevators, and through which the water above piston B passes to the cylinder A, beneath said piston, as it rises in the cylinder.

D is the ordinary source of supply from an overhead tank or from the street-mains, while E represents the ordinary eduction-valve operated by the hand-rope and through which the water beneath piston B is discharged as said piston descends.

Now, according to my invention, when using water under high pressure, such as is supplied by many hydraulic or other companies, or such as may be obtained from a pump, I connect the ordinary circulating-pipe C, by means of pipe c, with a cylinder F, provided with a piston, G, the rod g of which works in a second cylinder, H, of smaller size, which is in direct communication with the high-pressure supply through pipe h.

The cylinder F is supplied with water from an overhead tank or cistern, I, the communicating-pipe between them being governed by 55 a check-valve, i. The supply to this cistern I is from cylinder A, beneath piston B, which, as it descends, forces the water beneath it through valve E and pipe J.

It will be understood that pipe c is provided 60 with a check-valve, k, while pipe D is provided with a valve which may be operated by hand or from the cage should the high-pressure ever give out; but unless this occurs it is not used. The supply and discharge through 65 pipe h is also governed by a valve, l, actuated by the ordinary hand-rope, either direct or by means of its connection with E, as shown. The capacity of cylinders A and F should be about 70 equal, so that the displacement from F will be sufficient to force piston B to the bottom of cylinder A, while piston g is so proportioned 75 with regard to the known pressure supplied through h as to give the desired pressure in cylinder H. The top of cylinder H being provided with a suitable stuffing-box, m, for piston g to work through, it is not necessary that cylinder F should be closed at the bottom.

The various parts being in the position represented and the apparatus ready to work, the 80 operation is as follows, it being first stated that the valve E is open, as between the circulating-pipe C and cylinder A, and valve l is open, as between cylinder H and discharge-pipe h o. The hand-rope is moved and closes 85 valve E, as between the circulating-pipe C and the bottom of cylinder A, which it opens to pipe J and cistern I. At the same time valve l is closed, as between H h o, and opened as to h h H, by which the water under high pressure is admitted to cylinder H. The water at 90 high pressure causes the piston or ram g in the cylinder H to rise, and consequently the piston G expels the water in cylinder F, through the pipe c, into the elevator-cylinder 95 A, thereby forcing the elevator-piston B downward, the water underneath the elevator-piston B being discharged into the tank I, as before described. When the piston G in cylinder F is rising, the water is prevented from 100 passing back into the tank I by the check-valve i, and thus the water is compelled to move through c into A. When it is desired that the piston B should rise, the hand-rope

is again moved, and the valves E and l brought to their former position, the pressure being thereby removed from under g and the valve E opened between C and A, thus equalizing the pressure on both sides of the piston B. The weight of the cage will then cause said piston to rise through the solid body of water. The water above it being prevented from passing back to cylinder F, by means of check-valve k, is compelled to pass through the circulating-pipe C to the under side of said piston. While this is taking place the high-pressure water from cylinder H has been discharged through pipes h o, and piston g descends in said cylinder, bringing with it piston G in cylinder F, which is kept filled, as the piston G descends, by the water which flows in from tank I through valve i.

It will be seen by the combination of parts described that the large volume of water required to fill the cylinder A is supplied at a moderate pressure from the cylinder F, while the amount of high-pressure water required to effect this operation is only equal to the capacity of the small cylinder H. It will also be seen that the large volume of water discharged from the large cylinder A is utilized for again supplying the cylinder A. In fact the large volume of water is simply circulated and never actually discharged, the only waste of water being that discharged from the descent of the piston in the small cylinder H, so that the apparatus is available for effective use where the water can be had in limited volumes, but at high pressure, and where an extended movement of the elevating-piston B is required. An important feature in this connection is that should the source of water at high power be cut off, the apparatus can still be worked from the overhead supply or other

source of supply at ordinary pressure, when such a supply is available.

What I claim, and desire and desire to secure by Letters Patent, is—

1. The combination, with the lifting-cylinder 45 and piston, circulating pipe, and valve of a hydraulic elevator, of a cylinder, F, containing a power-actuated piston and connections between the cylinder F and the bottom and top of the lifting-cylinder, whereby the water discharged from the bottom of the lifting-cylinder 50 is subsequently forced into the top thereof, substantially as described.

2. The combination, with the lifting-cylinder, circulating-pipe, inlet and discharge pipes, 55 and valve of a hydraulic elevator, of the cylinders F and H of different diameters, provided with connected pistons, the tank I, communicating with the discharge-pipe of the lifting cylinder and with the cylinder F, the 60 high-pressure inlet-pipe communicating with the small cylinder H, and the discharge-pipe of the cylinder H, substantially as described.

3. The combination, with the lifting-cylinder, its inlet, outlet, and circulating pipes and 65 valves, of the cylinders F and H of different diameters, having connected pistons and valve l, controlling the flow of fluid to and from the small cylinder H, the tank I, communicating with the discharge-port of the lifting-cylinder 70 and with the cylinder F, and connections between the two valves, whereby they are caused to turn together, substantially as described.

In testimony whereof I have hereunto signed my name in the presence of the two subscribing witnesses.

WM. AUG. GIBSON.
